UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PLURAL LAMP-SOCKET.

No. 898,824.

Specification of Letters Patent. Patented Sept. 15, 1908

Application filed February 28, 1907. Serial No. 359,885.

To all whom it may concern:

Be it known that I, REUBEN B. BENJAMIN, a citizen of the United States, residing at Chicago, in the county of Cook and State of Illinois, have invented new and useful Improvements in Plural Lamp-Sockets, of which the following is a full, clear, concise, and exact description, reference being had to the accompanying drawing, forming a part 10 of this specification.

This invention relates to an improvement in plural lamp-sockets, and particularly to a type of lamp-socket which is provided with a plug having suitable contacts adapted to operate with the contacts of an ordinary lamp receptacle.

The object of the invention is the provision of a device of this class which is simple in construction and economical in manufacture, 20 and, at the same time, efficient and durable.

In the drawings Figure 1 shows, in central vertical section, a form of device embodying my invention; Fig. 2 is a cross-sectional view of the same, the section being taken on the line 2—2 of Fig. 1, looking in the direction indicated by the arrows; and Fig. 3 is a view similar to Fig. 1, but shows a modified form of the device.

In the several figures, in which like reference characters indicate the same parts throughout, 30 5 is a plug provided with a centrally-disposed projection 6 on its outer end. Sleeved on the plug 5 is a shell 7, forming the outer contact of the plug. This shell has an 35 inturned outer end 8 and an outturned inner end 9, forming a flange extending around the shell. Secured to the flange 9 is a plate 10, this plate being circular and having a central circular opening 11 through which extends a 40 projection 12 on the inner end of the plug 5. This projection 12 centers the plate 10 on the plug. The plate 10 is formed with wings or extensions 14 and 15, which extensions constitute the center contacts for the lamps. 45 The plate 10 is secured to the flange 9 by screws 16.

The plug 5 is formed with a central opening 17 through which extends a bolt 18, the upper end of which constitutes the center contact for the plug and upon the lower end of which is supported a plate 19. This plate 19 carries an outer contact for each of the lamps, and when the device is adapted for lamps of the Edison type, this plate 19 will 55 carry the lamp sockets 20 and 21.

A sleeve 22, which may be formed of a short piece of fiber tubing or the like, is sleeved on over the inner end of the bolt 18 and abuts the inner end of the plug. When the bolt 18 is tightened to secure the plate 19 in place, 60 this plate 19 will be drawn up into engagement with the sleeve 22 and by this means a rigid structure is made. An outer casing or cover 23 is provided with openings through which extend the lamp-holding shells 20 and 21 and engages around its upper edge, the edge of a disk 24. This disk 24 is formed of fiber or the like and is provided with a central opening through which extends the plug. This disk forms one side of the casing of the 70 device. Insulating sleeves 25 and 26 surround the lamp holding shells 20 and 21, and outside of these insulating sleeves are metallic rings or sleeves 27 and 28 secured to the cover 23.

In the form of the device shown in Fig. 3 a ring 29, formed of cylindrical wire, is adapted to assist in holding the lamp-shells 20 and 21 in place and to give added rigidity to the structure.

Having thus described my invention, what I claim as new and desire to secure by Letters Patent is:

1. In a plug-cluster, a plug adapted to operate with a suitable socket and carrying 85 a plurality of lamp-holding devices, said plug having a center contact upon its outer end and an outer contact member extending longitudinally thereof, a plate secured to the inner end of said outer contact member and forming an inner lamp-terminal-contact, and 90 a plate in electrical connection with the center contact of said plug, said last-named plate carrying a plurality of lamp holding devices.

2. In a plug-cluster, a plug adapted to 95 operate with a suitable socket and carrying a plurality of lamp-holding devices, said plug having a center contact upon its outer end and an outer contact-member extending longitudinally thereof, a plate secured to the 100 inner end of said outer contact member and forming an inner lamp-terminal-contact, and a plate in electrical connection with the center contact of said plug, said last named plate carrying the outer contact for each of 105 the lamp-holding devices.

3. The combination with a plug, of an outer contact member extending longitudinally of the plug and having a flange on its inner end, an inner lamp-terminal-contacting 110

- plate supported by said flange, an inner contact member on said plug, a plate electrically connected with said inner contact member and a plurality of lamp-holding devices supported thereby.
4. In a plug-cluster, the combination of a plug carrying a plurality of lamp-holding devices, a central contact upon the outer end of said plug, means for providing electrical connection between said center contact and the outer contacts of the lamps, an outer contact member upon said plug, said member being formed with a shoulder adjacent the inner end of the plug, and a contact-plate supported by and in electrical connection with said shoulder, said plate being adapted to engage the center contact of a lamp.
5. In a plug-cluster, the combination of a plug carrying a plurality of lamp-holding devices, a center contact upon the outer end of said plug, means providing electrical connection between said center contact and the outer contacts of the lamps, an outer contact member upon said plug, said member being formed with an outturned end adjacent the inner end of the plug, and a contact member supported by and in electrical connection with said outturned end and adapted to engage the center contact of each of the lamps.
6. In a plug-cluster, a plug of insulating material carrying a plurality of lamp-holding devices, a center and an outer contact mem-

ber upon said plug to cooperate with the contact of a suitable socket, said outer contact member having a flange upon its inner end, a plate supported by said flange and adapted to engage the center contact of a lamp, a bolt extending longitudinally through the plug, and a plate carried by said bolt, said plate being adapted to conduct current to the outer contacts of a plurality of lamp-holding devices.

7. In a plug-cluster, a plug, a center contact member extending therethrough, a plate supported by said member, a plurality of threaded shells carried by said plate, and a casing having openings for the reception of lamps, said shells being arranged in said openings and supporting said casing.

8. In a plug-cluster, the combination of a casing having openings, a sleeve extending outwardly from each of said openings and fixed to said casing, threaded shells in said sleeves supporting said casing, a plug, a member extending centrally through said plug and supporting said shells and conducting current thereto.

In witness whereof, I have hereunto subscribed my name in the presence of two witnesses.

REUBEN B. BENJAMIN.
